CLOTHING ACCESSORIES

John C. Owen, Jefferson City, Tenn.

Application March 9, 1953, Serial No. 341,211

5 Claims. (Cl. 2—279)

This invention relates to improvements in clothing accessories, and more particularly to a simulated ornamental handkerchief that may be worn in a breast pocket or any other place for ornamental effect.

It is customary for men to wear handkerchiefs in the breast pockets of coats, with the fabric protruding for ornamental effect. Such handkerchiefs are usually folded but are difficult to maintain in place and are often bulky.

Various devices have been proposed heretofore as a substitute for such ornamental handkerchiefs, but these have not been satisfactory because of the weight and bulk usually involved, complexity and expensiveness of manufacture, and other objections incidental to use thereof.

One object of this invention is to improve the construction of accessories of this type by providing for the support and exposition of ornamental handkerchief material in a holder which may be worn concealed in a pocket without bulkiness and which will be stable and effective in its support of the material.

A further object of the invention is to provide an accessory of the character described which uses a holder that is simple and inexpensive to manufacture and is compact and without bulkiness in service for effectively retaining the ornamental material that may be retained therein.

Still another object of the invention is to provide a holder for an accessory of the character described which may be adjustable to different lengths for accommodating itself to different sized pockets whereby the holder will be stable in its position in the pocket and will maintain the ornamental effect of the material.

These objects may be accomplished according to one embodiment of the invention by means of a plurality of plates connected together in clamping relation to retain the ornamental material therebetween and which will effectively hold the latter against working out of the holder or being displaced relative thereto. Provision is made also for an adjustment of the overall length of the holder to accommodate itself to different sized pockets. This may be accomplished according to this embodiment of the invention by an additional plate adjustably connected with one of the other plates and capable of being displaced lengthwise relative thereto to vary the overall length of the device or the support of the holder in the pocket and thereby to ensure of the proper degree of ornamentation exposed at the edge of the pocket.

This embodiment of the invention is illustrated in the accompanying drawings in which:

Fig. 1 is a perspective view of a portion of a garment showing the invention applied thereto;

Fig. 2 is a side elevation of the ornamental fabric material detached;

Fig. 3 is a top plan view of the accessory;

Fig. 4 is a perspective view of the clamping plates, separated or exploded;

Fig. 5 is a front elevation of the accessory complete;

2

Fig. 6 is an edge view thereof; and

Fig. 7 is a detail cross-section on the line 7—7 in Fig. 5.

The invention is shown in Fig. 1 as applied to a garment of the character of the coat, generally designated at C, and having the usual breast pocket P thereon, in which the accessory may be received and accommodated.

The accessory comprises an ornamental strip of fabric, generally designated at 1, which may be a section of handkerchief material or of any other ornamental fabric. One or more pieces may be used to provide the fabric 1, cut and finished as desired, with or without an ornamental border or ornamentation applied thereto.

The ornamental fabric 1 is adapted to be secured and retained in a holder comprising a plurality of plates shown at 2, 3, and 4. These plates 2, 3, and 4 may be made of any suitable thin, rigid, lightweight material, such as plastic, Celluloid, sheet metal, or the like. They may be curved horizontally, in arcuate form, as indicated in Fig. 3, to permit the assembly to fit neatly and comfortably in the pocket, although if somewhat flexible, the plates will conform to the shape of the body without initial pre-set curvature.

The lower central portion of the face plate 2 is cut away or notched at 5, and likewise the upper center portion of the height-adjusting plate 4 is cut away or notched at 6 to minimize use of material and to reduce weight. The plate 4 extends in bridging relation between the lower ends of the legs thus formed on the face plate 2, and may project below the lower edge thereof if desired, as hereinafter described. The plates 3 and 4 are adapted to be secured in face-to-face relation with the face plate 2 substantially as will be evident from Figs. 4 and 5.

The fabric material 1 is clamped between the upper edge portion of the face plate 2 and the adjacent opposed clamping plate 3 which are brought together and secured in clamping relation. In the example illustrated this clamping action is obtained by rigid, flat headed buttons 7, arranged in pairs at opposite edges of the face plate 2, adjacent the upper end thereof. Each of the buttons 7 has a shank slightly longer than the thickness of the clamping plate 3 so as to receive and clamp the latter as well as the material 1, interposed between the plates. The clamping plate 3 is provided with means for cooperating with the buttons 7 to secure the plates together. This means is shown as comprising slotted holes 8 and notches 9 in the clamping plate 3. The notches 9 are formed in the lower edge of the plate 3, and may slip behind the heads of the lower buttons 7, over the shanks thereof, while the heads of the upper buttons are inserted through the holes 8, then upon outward sliding movement of the plate 3 relative to the plate 2, the notches formed at one side of the holes 8 and the notches 9 will engage behind the heads of the buttons 7 for clamping the plates 2 and 3 with the fabric 1 interposed therebetween, thus securely fastening the pieces of fabric in place.

Punched depressions 10 in the rear face of the plate 2 and complementary projections 11 on the front face of the plate 3 are arranged to interfit or register with each other, thereby forming a clamping action with the fabric 1 therebetween for holding the piece of fabric securely in place. Any suitable means may be used for this purpose, as desired.

The height-adjusting plate 4 is adapted to be secured adjustably to the face plate 2 to be retained in different adjusted positions relative to the latter so as to vary the overall length of the holder according to the depth of pocket in which it is to be used. As an example of such adjusting means I have shown a pair of rigid, flat headed buttons 12, with a shank of substantially the same length

as the thickness of the plate 4, and rigidly attached to the lower outer portions of the plate 2. A pair of such buttons 12 will be sufficient. A row of slotted holes 13 is formed in each opposite end of the plate 4, where the latter overlaps the legs on the plate 2 so that a pair of holes 13 is in position to receive the pair of buttons 12, slipping over the heads of the buttons and having the notches engaging the shanks thereof behind the heads, thus clamping the plate 4 securely to the plate 2. The formation of the notches 14 in the lower sides of the holes 13 serves to retain the plate 4 in its adjusted position relative to the plate 2 against accidental displacement because the weight of the holder will tend to maintain the connection. The plate 4 may be adjusted in position relative to the plate 2 by disengaging the slotted holes 13 from the buttons 12 and reconnecting the parts through another pair of slotted holes so as to provide a holder of the proper length to fit the pocket P in which it is to be accommodated. Any suitable number of slotted holes may be provided according to the size of the plate and the need for adjustment.

A short upwardly inclined pin 15 may be attached to the center upper portion of the face of the plate 2 to catch in the fabric of the pocket and thus prevent the holder from slipping out of its normal position. Such a pin may be used if desired, although not necessarily required since the weight of the holder ordinarily will be sufficient for the purpose.

The use of the accessory will be evident from the foregoing description. The holder may be removed for replacement or cleaning of the fabric when desired. The fabric may be removed easily and quickly from the holder and a second strip of fabric substituted therefor in a simple and expeditious manner.

This accessory has distinct advantages over the conventional folded handkerchief because of its neatness, stability of position, convenience and lessening of bulk in the pocket. The device may be manufactured simply and inexpensively and used to provide an effective and ornamental simulation of the folded handkerchief as often desired.

While the invention has been illustrated and described in one embodiment, it is recognized that variations and changes may be made therein without departing from the invention as set forth in the claims.

I claim:

1. A pocket ornament comprising a piece of fabric having an upper end portion adapted to protrude from a garment pocket to simulate in appearance a folded handkerchief and a lower end portion adapted to be supported within said pocket, and a holder for the lower portion of said piece of fabric adapted to be located entirely within said pocket, said holder including a first holder plate, a second holder plate and means for detachably connecting said plates together in face-to-face relation with said lower end portion of said piece of fabric clamped therebetween, whereby said piece of fabric may be attached to or removed from said holder by connecting or detaching said plates, and a prong fixed at one end to one of the plates with a pointed outer end upwardly inclined to engage in the pocket.

2. A pocket ornament comprising a piece of fabric having an upper end portion adapted to protrude from a garment pocket to simulate in appearance a folded handkerchief and a lower end portion adapted to be supported within said pocket, a first holder plate of a height less than the depth of the pocket in which the ornament is to be placed, a second holder plate of a height at least as great as that of said first holder plate but less than the depth of the pocket in which the ornament is to be placed, means for detachably connecting said holder plates together in face-to-face relation with said lower end portion of said piece of fabric clamped therebetween, a height adjusting plate, and means adjustably connecting said height adjusting plate to one only of said holder plates

so that its lower edge is below the lower edge of said second holder plate a distance which may be altered to adapt the ornament for use in pockets of different depths, whereby said piece of fabric may be removed from said holder plates without disturbing the height adjustment of the ornament and the height of the ornament may be altered without removing said piece of fabric from said holder plates.

3. A pocket ornament comprising a piece of fabric having an upper end portion adapted to protrude from a garment pocket to simulate in appearance a folded handkerchief and a lower end portion adapted to be supported within said pocket, a holder for the lower portion of said piece of fabric adapted to be located entirely within said pocket, a first holder plate having a pair of spaced apart apertures therein, each of which apertures includes a wide portion and a narrow portion on one side of the wide portion, the narrow portions of both of said apertures being on the same sides of said wide portions, a second holder plate, and a pair of headed buttons secured to one face of said second holder plate in spaced apart relation to cooperate with the apertures in said first holder plate to detachably connect said holder plates together in face-to-face relation with the lower end portion of said piece of fabric clamped between the holder plates in the zone between said buttons, each of said buttons including a head portion of such size and shape that it may pass through the wide portion of one of said apertures but cannot pass through the narrow portion of such aperture and a stem portion slightly longer than the thickness of the first holder plate and of a cross-section such that it may pass through the narrow portion of such aperture.

4. A pocket ornament comprising a piece of fabric having an upper end portion adapted to protrude from a garment pocket to simulate in appearance a folded handkerchief, and a lower end portion adapted to be supported within said pocket, a holder for the lower portion of said piece of fabric adapted to be located entirely within said pocket, said holder including a first holder plate having a pair of spaced notches in one edge and a pair of spaced apertures therein, each of said apertures including a wide portion and a narrow portion on the side of said wide portion remote from said one edge, a second holder plate, and first and second pairs of headed buttons secured to one face of said second holder plate in spaced apart relation to cooperate respectively with said apertures and notches in said first holder plate to detachably connect said holder plates together in face-to-face relation with the lower end portion of said piece of fabric clamped between the holder plates in the zone between said buttons, each of the buttons of said first pair including a head portion of such size that it may pass through the wide portion of one of said apertures but cannot pass through the narrow portion thereof and a stem portion slightly longer than the thickness of said first holder plate and of a cross-section such that it may pass through the narrow portion of such aperture, each of the buttons of said second pair including a stem portion of a length slightly greater than the thickness of said first holder plate and of a cross-section such that it may pass through one of said notches and a head portion of such size that it cannot pass through such notch.

5. A pocket ornament comprising a piece of fabric having an upper end portion adapted to protrude from a garment pocket to simulate in appearance a folded handkerchief and a lower end portion adapted to be supported within said pocket, a first holder plate on one side of the lower end portion of said piece of fabric including a fabric contacting face having a plurality of small indentations therein, a second holder plate on the opposite side of the lower end portion of said piece of fabric including a fabric contacting face having a plurality of small projections thereon opposite said indentations, said first and second holder plates being of such sizes as to permit them to be disposed entirely within the garment pocket in which

the ornament is to be used, and means detachably connecting said holder plates together with the lower end portion of said piece of fabric clamped therebetween, said projections and indentations cooperating to grip the fabric therebetween to prevent the removal of the piece of fabric from between the connected holder plates.
